UNITED STATES PATENT OFFICE.

MICHAEL J. GOGARTY, OF BROOKLYN, NEW YORK.

LOADING AND UNLOADING DEVICE.

1,085,032.

Specification of Letters Patent. Patented Jan. 20, 1914.

Application filed April 27, 1912. Serial No. 893,543.

To all whom it may concern:

Be it known that I, MICHAEL J. GOGARTY, a citizen of the United States, residing at Brooklyn, in the county of Kings and State 5 of New York, have invented new and useful Improvements in Loading and Unloading Devices, of which the following is a specification.

This invention relates to loading and unloading devices and refers more particularly to that type which are adapted to pick up a load from the ground, transport or convey the same to any desired point, and unload the same at the level at which the load was 15 received or at an elevated point.

A further object of the invention is the provision of means for elevating the boom bodily, whereby the weight of the loaded bucket and the boom may be removed from 20 the supporting wheels and placed on the vehicle, so that the boom may be swung laterally without friction for dumping the load to one side of the vehicle and so as to steady the vehicle and prevent the same 25 from lateral tilting.

A further object of the invention is the provision of means for raising the boom and boom structure with its weighted bucket thereon, so that the boom may be readily 30 turned without friction for dumping the contents of the bucket to one side of the vehicle and for automatically unlocking the boom so that it may be turned as desired.

Still another object of the invention is the 35 provision of simple and efficient means for automatically throwing into operative position a support or strut which will remove the weight of the boom and the weighted bucket from its pivotal connection immediately upon the initial movement of the 40 bucket toward an elevated position upon the boom.

A still further and the most important object of the invention is to construct the 45 boom and the bucket in such manner that the bucket may be carried throughout its length on the boom with its bottom in a level position or with the bucket tilted rearwardly in order that the device may be accommodated to the loading and unloading of different materials which vary in consistency 50 from solids to plastic materials.

Still another object of the invention is the 55 provision of means for automatically tilting the bucket as the same makes its initial movement upon the boom and for automati-

cally closing a door on the bucket which serves to retain material therein.

A further object of the invention will appear as the following specific description is 60 read in connection with the accompanying drawings, which form a part of this invention, and in which—

Figure 1 is a detail side elevation. Fig. 2 a top plan view thereof. Fig. 3 a side elevation showing the boom and its associated parts in raised position. Fig. 4 is a detail side elevation illustrating in dotted lines the position of the bucket in dumping position. Fig. 5 a similar view showing the 70 alternative position of the tilting lever. Fig. 6 a detail rear elevation of the bucket. Fig. 7 is a detail elevation taken from the inside of one of the boom legs and showing the adjusting mechanism. Fig. 8 is a detail 75 elevation showing the switch controlling lever. Fig. 9 is a side elevation of a modified type of bucket with the door in open position. Fig. 10 is a similar view showing the door in closed position. Fig. 11 a detail 80 elevation showing the method of adjusting the tilting lever used in the structure illustrated in Figs. 9 and 10. Fig. 12 is a detail sectional view showing the method of adjusting the boom legs to accommodate different size buckets; and Fig. 13 is a side 85 elevation of the structure. Fig. 14 is a detail inside elevation showing a modified form of tilting track and tilting track lock.

In carrying out the present invention I 90 preferably provide a truck platform 1 of any suitable character which is supported upon wheels 2 preferably so constructed that they may be conveniently turned in any suitable manner so as to steer the vehicle. 95 Mounted upon the forward end of the truck and depending therefrom is a suitable bracket 3 and a similar or corresponding bracket 4 is extended forwardly in the plane of the platform 1, both brackets centrally 100 apertured in vertical alignment so as to receive the pivoting post 5 of the boom. This boom as has been illustrated in Figs. 1 to 3, is constructed of separated legs 6 joined together at their outer ends by a rod 7 which 105 carries a pulley 8 for the bucket operating cable or rope 9. The inner end of the boom has secured thereto converging brace members 10 connected together by an upright 11 which extends between the outer ends at the 110 apex of the convergence. These converging brace members have the post 5 secured di-

rectly thereto and in such manner that it is rotatably and vertically movable in the brackets 3 and 4. The boom and its associated parts are normally supported upon 5 wheels 12 secured to the sides of the leg 6 at the juncture thereof with the brace members 10 and by caster wheel 13 secured to the apex of the lower brace members 10.

The boom is, under normal circumstances, 10 locked in alignment with the vehicle by a yoke-shaped lever 14 pivoted upon the platform 1 as shown at 15, and provided with an angular rear end 16 for a purpose to be hereinafter described. The forward ends 15 of the lever are provided with pins 17 which are engaged in apertures formed in suitable plates 18 extended between the brace members 10 and a rigid strut 19 extending between the legs of the boom. Also pivoted 20 upon the platform as shown at 20, is an operating lever 21 having a yoke end 22 pivotally connected with a collar 23 freely mounted upon the post 5. The collar 23 is arranged between collars 24 and 25 which are keyed to the post and carry suitable ball 25 bearings as will be readily understood. The rear end of the lever 21 is positioned between the legs of a bifurcated bracket 26 in which is pivoted a cam lever 27 adapted to operate 30 the lever 21 so as to elevate the post thereby, carrying with it the boom and its associated mechanism and lifting the wheels 12 and 13 off the ground, as shown in Fig. 3. Simultaneously with the depression of 35 the rear end of the lever 21 by the cam lever 27, this lever 21 will engage the angular upturned end 16 of the lever 14 to press the same and raise the pins out of the apertures in the plates 18 so as to unlock the boom and permit the same to be turned to 40 either side. In order to turn the boom in the brackets 3 and 4 there is journaled in bearings 28 mounted upon the platform 1, a shaft 29 carrying drums 30 and 31 and a hand wheel 32. Wound around the drums 45 30 and 31 in opposite directions, are turning cables 33 which are connected to opposite sides of the braces 10 so that when the wheel 32 is rotated in one direction the 50 boom will be turned upon its pivotal point, as desired. The reversal of the wheel will, of course, bring the boom back to normal position.

The boom legs 6 are each constructed in 55 separate sections 34 and 35 hinged together at 36 and with the inner section 35 connected to the upper brace members 10 by horizontal track sections 37, the purpose of which will be hereinafter described. The 60 section 35 of each leg carries a bracket 38 adapted to receive a bolt 39 which extends through the same and engages an arcuate adjusting arm 40 carried by the outer section 34, this arm being provided with a plurality of apertures 41 as shown, so as to ad-

justably receive the bolt 39. In this manner the angular relation of the sections 34 and 35 may be adjusted as is indicated in dotted lines in Fig. 3. Each leg 6 carries separate track sections 42 and 43 which are connected together at the juncture of the two sections 34 and 35 by a switch plate 44 and each leg is provided with a pivoted or tiltable track section 45 which is provided with an abutment 46 at its outer end and is connected by a rod 47 to the opposite tiltable section.

The bucket indicated at 48 is provided with a transverse rod 49 extending across its open front and provided with rollers 50 which travel in the track on opposite legs of the boom. The rear closed end of the bucket has secured thereto bearings 51 in which is journaled a shaft 52 having right-angled crank ends 53 which project beyond the sides of the bucket and are provided with rollers 54 also adapted to travel in the tracks on opposite legs of the boom. Suitable cleats 55 secured to the rear of the bucket, are provided to slidably receive locking bolts 56 which engage the crank end of the shaft 52 and lock the same in either raised or lowered position, as shown in Fig. 6. When these crank ends are lowered as shown in full lines in Fig. 6, the bucket will travel up the tracks with its bottom in horizontal position as shown and when the crank ends 53 are in raised position as shown in dotted lines in Fig. 6 the bucket will travel over the tracks in an inclined position as shown in Fig. 5. In order to throw the bucket to horizontal position when the bucket is returned to loading position, I provide a switch tongue 58 which is pivoted at the intersection of each of the track sections 42 and 37 and is controlled by a lever 59 on the outside of the boom legs. This lever carries a bolt in its free end which is adapted to engage in apertures 60 formed in the sections 35. The switch is thrown downwardly as shown in Fig. 5 when the ends 53 of the shaft 52 are elevated as shown in Fig. 6 in dotted lines, so that the rollers 54 will be deflected onto the track sections 37 and the rear end of the bucket elevated so as to bring its bottom in horizontal position, as shown in Figs. 1 and 3. The upper end of the bucket is provided with a cross bar 61 to which the end of the cable 9 is connected. This cable passes from this connection with the cross bar 61 under the pulley 8 and over a pulley 62 swiveled upon the top of the post 5 and to an ordinary winch (not shown) which, as will be readily understood, is provided for raising and lowering the bucket on the tracks.

In order to support the boom and remove the strain from its pivotal connection with the brackets 3 and 4 when the bucket is elevated, there is pivoted to each section 35

of the boom a yoke-shaped member 63 adapted to be held in inoperative position by the ends of the bar 61 contacting with the same when the bucket is in loading position as shown in Fig. 1. As the bucket is moved forwardly on the tracks the rear end of the yoke member 63 will be released and the forward or heavy end of said yoke member will drop by gravity into engagement with the ground. A suitable shoulder 64 is formed on each leg of the yoke member and is adapted to engage beneath brackets 65 secured to the sections 35. As soon as the bucket is returned to normal position the bar 61 will contact with the rear end of the yoke member and raise its supporting legs from the ground automatically and thus permit the vehicle to be moved forwardly to pick up another load.

In the modification illustrated in Figs. 9, 10 and 11 the bucket 48 has secured to opposite sides thereof separated rack bars 65 between which are adjustably mounted the bearing blocks 66. These bearing blocks carry stub shafts 67 upon which are pivoted suitable levers 68 carrying rollers 69 at one end thereof to engage the tracks upon the opposite legs of the boom. The ends of the levers opposite the lower ends are connected together in any suitable manner and have secured thereto one end of the cable 9 so that immediately the tension is applied to the cable, the levers will be turned upon their stub shaft 67 and the forward portion 30 of the body elevated as indicated in Fig. 10. In this instance, the rear rollers of the bucket are indicated at 70 and have no relative movement with relation to the bottom of the bucket. It will, of course, be understood that the rack bars 65 may be dispensed with and the stub shafts secured directly to the sides of the casing. In this modification it will also be seen that I have pivoted to the forward end of the bucket a combined scoop blade and door 71 which is connected to the opposite end of the levers 68 by links 72 so that when the levers 68 are operated the combined scoop blade and door will be thrown to closed position, thus 40 making it possible for the bucket to pick up and hold more material than where the same is only provided with the stationary scoop blade and is tilted as before described.

While it is understood that these machines 55 may be used for loading and unloading different materials which as has before been stated may be of the consistency of solids or of plastic or semi-plastic materials, it may be here stated that in using the devices for 60 loading carts or other vehicles with snow and such materials from the street, it will be necessary to use a comparatively wide bucket. By changing the size of the bucket the same identical machine may be used for 65 loading, unloading and transporting sand,

cement or like material, but in order to do this it is necessary to change the width between the separate legs of the boom. For this purpose I have devised the modified form of structure illustrated in Figs. 12 and 13 wherein the brace members 10, 11 and 19 have secured thereto suitable lugs 73 in which a shaft 74 is secured. The sections 35 are slidably mounted upon this shaft toward and away from each other and are held in adjusted position by means of the collars 75 which are keyed to the shaft by the set screws 76. The brace members have also secured thereto lugs 77 in which a shaft 78 is secured and adjustably mounted upon this shaft are the track sections 37, the latter being held in adjusted position by the collars 79 and the set screws 80. The outer end of the boom in this instance may be adjusted in any suitable manner, for instance, by making the rod in adjustable sections or by pivotally connecting the opposite legs of the boom by separate bars and bridging across these bars a shaft to hold the pulley 8.

As shown in the drawings the post 5 has its upper end braced by diagonal struts 81 connected to a collar 82 at its upper end, which collar surrounds the shaft and is adjustably secured thereto by means of a set screw 83, the lower end of the struts being secured to the braces 10 as shown. Similar struts 84 are secured to the platform 1 and to a collar 85 which is loosely mounted upon the post so as to permit said post to move vertically therein or to rotate.

In the operation of the device the vehicle is propelled in any suitable manner so as to force the scoop blade on the bucket into a pile of material. When the bucket has been forced far enough into the material and properly loaded the vehicle is stopped and the winch operated so as to wind up the cable 9 and thereby draw the bucket over the tracks on the boom. When the rollers 105 strike the abutment 46 on the pivoted track section the bucket will be tilted to the position shown in dotted lines in Fig. 4, thereby discharging its contents. Upon the initial movement of the bucket it will be seen that 110 the yoke member 63 is released by the bar 61 and the lower supporting legs will then drop by gravity into engagement with the ground at the same time carrying their shoulders 64 beneath the brackets 65, thus 115 taking the strain of the boom off of the pivotal point and greatly aiding in the support of the weighted bucket. When the bucket is returned to normal position the yoke supporting member will be tripped and 120 thrown to inoperative position as shown in full lines in Figs. 1 and 3. When it is desired to incline the bottom of the bucket upon being elevated on the boom, the crank 125 ends 53 are raised to the position shown by 130

dotted lines in Fig. 6 and the switch 58 depressed so that the rollers 54 will travel in the track section 37. When these rollers strike the inclined portion of the track they, 5 with the rollers 50 being in a parallel plane with the bottom of the bucket, will throw the bottom of the bucket to an incline parallel with the inclined track thus any soft stuff within the bucket will be thrown to 10 the back of the same and a greater quantity of material may thereby be loaded and elevated. After loading the bucket and partially elevating the same upon the boom if it is desired to turn the boom so as to dump 15 the contents of the bucket into a cart or wagon at one side of the vehicle, the cart lever is depressed to the position shown in Fig. 3 which action elevates the forward end of the lever 21 and raises the post 5 and the 20 entire boom mechanism from the ground. By then rotating the hand wheel 32 in the proper direction the boom may be turned as is indicated in dotted lines in Fig. 2. The elevation of the bucket on the boom may be 25 then continued until it is brought into dumping position as shown in Fig. 4. By adjusting the separate sections 34 and 35 of the boom, the outer section 34 may have any inclination desired and it is to be understood 30 that while I have shown only a simple form of accomplishing such adjustment, that I may resort to many modifications thereof in order to accomplish the desired result and without departing from the spirit or scope 35 of the invention.

The outer end of the boom is preferably elevated by means of a block and fall arrangement, the blocks being connected to the outer end of the boom and to the post 5 as shown, and the free end of the rope being 40 connected to a cleat 86 carried by the lower end of the post.

In the modification shown in Fig. 14, the 45 tilting track sections 45 are locked in position to receive the bucket upon its upward movement over the boom by means of spring bolts 87 which engage the cleats 88 carried by the sections 34. These spring bolts are released from the cleats by means of the 50 link 89 having depending ends 90 which lie in the path of the rollers 50. When the bucket is advanced on the boom to the position where it would ordinarily engage the abutment 46, the rollers 50 engage the depending ends 90 on the links 89 and release the bolts 87 from the cleats 88, thus permitting the track section 45 to tilt and the bucket to dump its contents. Upon the retrograde movement of the bucket, the track 55 will be returned to normal position and the spring bolts will snap upon the cleats 88, thus locking the track sections 45 in alignment with the sections 34.

What is claimed as new is:

65 1. In combination, a portable truck, a boom

pivoted thereto, means for locking the boom in alinement with the truck, means carried by the truck for raising the boom bodily means actuated by the raising means for releasing the locking means and a bucket 70 mounted to travel over the boom.

2. In combination, a portable truck, a boom pivoted thereto, a lever pivoted to the truck for locking the boom in alinement with the truck, means carried by the truck 75 for raising the boom bodily, said means actuating the lever to release the same from locking engagement with the boom, means for turning the boom and a bucket mounted to travel over the boom.

3. In combination, a portable truck, a boom pivoted thereto, a lever pivoted to the truck for locking the boom in alinement with the truck, means carried by the truck 80 for raising the boom bodily, said means actuating the lever to release the same from locking engagement with the boom, a drum shaft carried by the truck, flexible elements connected to the drum shaft and to the boom, means for rotating the drum shaft 85 and a bucket mounted to travel over the boom.

4. In combination, a portable truck, brackets carried thereby, a boom, a pivotal member carried by the boom and slidably 90 and rotatably arranged in the brackets, means for supporting the boom, means for raising and lowering the boom bodily, means controlled by the raising and lowering means for locking the boom in alining position with the truck and a bucket mounted 100 to travel over the boom.

5. In a loading and unloading machine, a pivoted boom, tracks carried thereby including a tiltable track section, a bucket, 105 rollers carried by one end of the bucket for engaging the tracks, rollers adjustably carried by the opposite end of the bucket for engaging the tracks, and means for moving the bucket over the tracks and for tilt- 110 ing said track section.

6. In a loading and unloading machine, a portable truck, a boom pivoted thereto, tracks carried by said boom including a tilt- 115 able track section, a bucket, stationary means carried by the bucket for engaging the tracks, a pivoted roller mounting device carried by the bucket engaging the tracks, and means for moving said bucket over the boom and for tilting said track section.

7. In a loading and unloading machine, a portable truck, an inclined boom carried thereby, tracks carried by the boom, a bucket, track engaging members carried by the bucket, means for raising and lowering 125 the bucket on the boom, auxiliary track sections, and switches for throwing the track engaging members onto the auxiliary track sections when the bucket is returned to its lowest position.

8. In combination, a boom, a bucket adapted to travel over said boom, and means carried by the boom and automatically controlled by the bucket for supporting the boom when the bucket is elevated thereon.

9. In combination, an inclined boom, a supporting member pivoted to the boom and adapted to drop by gravity and to engage the ground for supporting the boom, coacting means with the supporting member and boom for removing the strain upon the pivot

point of the member, a bucket operating over the boom, and means carried by the bucket for throwing the supporting member to inoperative position.

In testimony whereof I affix my signature in presence of two witnesses.

MICHAEL J. GOGARTY.
